(57) **CLAIM**

The ornamental design for a spinning toy, as shown and described.

DESCRIPTION

FIG. 1 is a first perspective view of a spinning toy showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the spinning toy thereof; and,

FIG. 10 is a perspective view of another state of the spinning toy thereof.

The broken lines shown in the drawings depict portions of the spinning toy that form no part of the claimed design.

1 Claim, 10 Drawing Sheets
